UNITED STATES PATENT OFFICE

GEORGE V. MACKINNON, OF ELKINS PARK, PENNSYLVANIA, ASSIGNOR TO JOHN B. STETSON COMPANY, OF PHILADELPHIA, PENNSYLVANIA, A CORPORATION OF PENNSYLVANIA

HAT MAKING METHOD AND APPARATUS

Application filed April 22, 1931. Serial No. 531,934.

My invention relates to a method of and apparatus for the manufacture of hat bodies of felt or the like having a reinforced or thickened brim edge, the body and integral edge to be sized and blocked in the production of finished felt hats.

In accordance with my invention, in the initial formation of the hat body, by deposit upon a cone, by application of suction, of the fur, wool or other felt constituents, the deposit thereof at the large or open end of the body is materially increased, yielding a band or edge integral and homogenous with and materially thicker than the remainder of the body, whereby, upon subsequent shrinking or sizing, the body with the integral thickened band or edge shrinks and increases in thickness yielding a sized body having at the edge of the portion destined to form the brim of the hat an integral enlargement or reinforcement, constituting an eventual reinforced brim edge which is plain, single-ply or simple, in the sense that it does not comprise folds or a plurality of layers worked, welded, 20 welted, felted, or otherwise attached or secured to each other.

In accordance with my invention the usual perforated cone, upon which is deposited under the influence of suction fur, wool or other fibres to constitute felt, is modified in structure or form to provide at its open end, or at any suitable region intermediate its open and closed ends, or at both places, a circumferentially extending perforated recess or channel to effect a deposit of fur or the like thicker than and integral with the adjacent portion or portions of the body, to constitute after subsequent sizing or shrinking a defined reinforcement thicker than and integral with the adjacent portion or portions of the sized hat body; more particularly, the effect of the suction applied at the recess or channel is greater than that applied at the adjacent portion or portions of the cone, as by utilizing 45 perforations in the recess or channel which

are larger than those in the adjacent portion or portions of the cone.

Further in accordance with my invention, fur or the like, aside from that which is distributed or delivered adjacent the cone for 50 usual deposition thereon, is delivered through a separate or independent path, as through a conduit, and delivered adjacent the revolving cone to a more or less sharply defined zone thereof where, under the influence of suction, 55 there is built up locally a defined deposit thicker than and integral with the adjacent portion or portions of the deposit upon the cone; the suction applied at the aforesaid zone may be and preferably is greater than that applied at other portions of the cone, as by providing in the zone aforesaid perforations of larger diameter than those of the adjacent portion or portions of the cone; 60 more particularly, the zone to which fur or the like is separately or independently delivered as aforesaid may be defined or determined by a recess or channel in the cone as aforesaid.

My invention resides in the method and apparatus of the character and for the purposes hereinafter described.

For an illustration of some of the various forms my apparatus may take reference is to 75 be had to the accompanying drawings, in which:

Fig. 1 is a vertical elevational and sectional view of apparatus for practicing my method of producing hat bodies;

Fig. 2 is a horizontal plan view, partly in section, taken on the line 2—2 of Fig. 1;

Fig. 3 is a vertical sectional view of a cone utilized in accordance with my invention;

Fig. 4 is a fragmentary sectional view, on 85 enlarged scale, of the cone at and adjacent the band or border forming channel;

Fig. 5 is an elevational view of the hat body with thickened band or border;

Fig. 6 is a fragmentary sectional view, on 90

enlarged scale, of the band or border and adjacent body;

Fig. 7 is an elevational view of the body and its band after sizing;

5 Fig. 8 is a fragmentary sectional view, on enlarged scale, through the reinforced brim edge of Fig. 7;

10 Fig. 9 is an elevational view of a modified cone structure having a channel for forming the reinforcement of the rim and/or brim adjacent their junction;

Fig. 10 is a sectional view of a hat embodying my invention;

15 Fig. 11 is a fragmentary sectional view, on enlarged scale, of a portion of the brim and its reinforced edge;

Fig. 12 is a fragmentary view, on enlarged scale, showing the brim and crown reinforced at and adjacent their junction.

20 Referring to Figs. 1 and 2, to the open upper end of the chamber or drum C, having the two doors 1 and 2 swinging outwardly upon their pivots 3 and 4, the fur, wool or other felt-forming fibres are delivered 25 through the chute or guiding structure 5 with which are associated the usual brush and picker rolls or cylinders 6 and 7 with which may be associated, as usual, a transversely extending series of steam jets 8 for moistening and blowing the fibres.

30 At the bottom of chamber C is provided the usual turntable 9 rotated by gear 10, driven by any suitable means, meshing with the circular rack or ring gear 11 upon the table 9, 35 which has an opening 12 covered by the cone K. Air is drawn through the perforations in the cone and thence through opening 12 by suction created by the exhaust fan or pump 13 disposed within the sub-base or 40 chamber 14 and driven by any suitable means, such as an electric motor M.

45 The cone K, as illustrated in Figs. 1, 3 and 4, is provided with a circumferential groove or channel 14 adjacent or immediately above the imperforate inwardly extending flange or ledge 15a, of the imperforate base 15, constituting an abutment for defining the end of the thickened deposit in channel 14. The wall of the channel 14 has extending 50 therethrough numerous holes or perforations 16, substantially uniformly distributed and preferably larger than the holes or perforations 17 distributed substantially uniformly over the remainder of the cone above the 55 channel 14.

60 The fur or fibres, passing downwardly from the delivery chute 5 in the chamber C, are drawn to and settle upon the revolving cone K, due to the applied suction, building up on the cone a hat body A, Figs. 5 and 6, of loose felt of usual or suitable thickness. At the same time there is deposited in the channel 14, under the influence of more intense suction, because of the larger apertures 65 or holes 16 therein or because of local appli-

cation of more intense suction otherwise produced, the band or border B, integral with the body A, and finally, after sizing, constituting a reinforced edge of the hat brim.

70 By the channel 14 the width of the thickened edge or band B is quite definitely determined, and its lower edge at the flange or ledge 15a is well defined in regularity and of sufficient uniformity and smoothness ordinarily to require no trimming, cutting or working before or after shrinkage to size or final dimensions. The band B, as indicated in Fig. 6, may, as to its excess in thickness over body A, be offset on the outer side, as effected by and at that upper portion of channel 14 at or adjacent its junction with the cone body k.

75 Fig. 10 is a sectional view of a hat embodying my invention;

80 Fig. 11 is a fragmentary sectional view, on enlarged scale, of a portion of the brim and its reinforced edge;

85 Fig. 12 is a fragmentary view, on enlarged scale, showing the brim and crown reinforced at and adjacent their junction.

90 Referring to Figs. 1 and 2, to the open upper end of the chamber or drum C, having the two doors 1 and 2 swinging outwardly upon their pivots 3 and 4, the fur, wool or other felt-forming fibres are delivered through the chute or guiding structure 5 with which are associated the usual brush and picker rolls or cylinders 6 and 7 with which may be associated, as usual, a transversely extending series of steam jets 8 for moistening and blowing the fibres.

95 At the bottom of chamber C is provided the usual turntable 9 rotated by gear 10, driven by any suitable means, meshing with the circular rack or ring gear 11 upon the table 9, which has an opening 12 covered by the cone K. Air is drawn through the perforations in the cone and thence through opening 12 by suction created by the exhaust fan or pump 13 disposed within the sub-base or chamber 14 and driven by any suitable means, such as an electric motor M.

100 The cone K, as illustrated in Figs. 1, 3 and 4, is provided with a circumferential groove or channel 14 adjacent or immediately above the imperforate inwardly extending flange or ledge 15a, of the imperforate base 15, constituting an abutment for defining the end of the thickened deposit in channel 14. The wall of the channel 14 has extending therethrough numerous holes or perforations 16, substantially uniformly distributed and preferably larger than the holes or perforations 17 distributed substantially uniformly over the remainder of the cone above the channel 14.

105 The fur or fibres, passing downwardly from the delivery chute 5 in the chamber C, are drawn to and settle upon the revolving cone K, due to the applied suction, building up on the cone a hat body A, Figs. 5 and 6, of loose felt of usual or suitable thickness. At the same time there is deposited in the channel 14, under the influence of more intense suction, because of the larger apertures or holes 16 therein or because of local appli-

110 cation of more intense suction otherwise produced, the band or border B, integral with the body A, and finally, after sizing, constituting a reinforced edge of the hat brim.

115 Upon completion of deposit, the doors 1 and 2 are swung outwardly, giving access to the cone for applying wet cloth or fabric over the hat body, whereupon the cone with the body thereon is removed. The body with its integral band B is then plunged into hot water, removed from the cone, and thereafter sized by usual methods.

120 While a channel 14 is preferred, the perforated band-forming zone may be the lower portion of the cone K without channel or recess.

125 Upon completion of deposit, the doors 1 and 2 are swung outwardly, giving access to the cone for applying wet cloth or fabric over the hat body, whereupon the cone with the body thereon is removed. The body with its integral band B is then plunged into hot water, removed from the cone, and thereafter sized by usual methods.

As shown, when conduit 18 is employed, it swings out with door 2 on which it is supported, giving free access to the cone. It will be understood conduit 18 may be otherwise disposed or supported, as fixedly upon and within chamber C, with its discharge end movable away from the cone or fixed in a position away from the doors 1 and 2 to allow free access to the cone.

10 The band B may be produced by the larger holes 16 or increased suction without the channel; or by the effect of the channel 14 with suitable intensity or degree of suction; or by the definite local delivery of fur or the 15 like to a restricted or defined zone of the cone. Any one or more of these features is or are effective; preferably all three are employed.

The band B is simple or plain, or single-ply, as distinguished from the case where the lower or brim forming end of the body A is of the thickness of the body itself, and then folded back upon itself, with or without stitching, forming a double-ply edge, 25 worked or felted together, and carried on through the remainder of the usual process of sizing or shrinking. In accordance with my method the thick band is preformed and complete before removal of the body from 30 the cone K.

The thickened border B is itself at its free edge left raw, untrimmed or uncut; however, if desired, it may be trimmed or cut more sharply to define or smooth its lowermost edge, though this has been found to be unnecessary.

The body A, with its integral thickened band B, is then carried through the usual sizing or shrinking process for simple hat bodies, the body A and band B both shrinking while increasing in thickness. This process is continued until there is reached a stage represented by Figs. 7 and 8, in which the body A has been reduced in size to that indicated by A', and its band has been reduced in length and increased in thickness as indicated at B'. Thereafter the sized body is blocked and finished. In this further treatment the band B' ordinarily requires no special treatment other than that applied to the remainder of the hat.

In Fig. 9, the cone K is provided with a recess or channel 14', having as in the case of Fig. 3 the holes or perforations 16. This 55 channel may be of any suitable width and located at any suitable position on the cone for procuring a deposit of materially greater thickness than the neighboring parts of the hat body. Here again, as in the case of the 60 channel 14 of the cone of Figs. 1, 3 and 4, there is produced a thickened deposit of fur or other fibres effecting a reinforcement or enlargement which is perceptibly locally defined, or abrupt in the sense that, while it is 65 not or need not be sharply or perfectly ab-

rupt, it is not merely a thicker portion of a hat body whose thickness changes or tapers gradually, or rather imperceptibly. In this example again, there is preferably used, though not necessarily, a conduit 18 functioning as described in connection with Figs. 1 and 2. It will be further understood that the cone K of Figs. 1 and 3 may have in addition to the channel or recess 14 one or more further channels or recesses located as and where desired, corresponding generally with the channel 14' of Fig. 9.

When a cone is provided with both channels 14 and 14' there is produced a hat having, as illustrated by Fig. 10, both a reinforced or thickened brim edge, and a reinforced or thickened region at the junction of the crown and brim.

After the body has been sized, as indicated in Figs. 7 and 8, it is blocked and finished as usual, without need for special treatment of the thickened edge B', which ordinarily requires no cutting, trimming or tooling, though these or other operations may be applied, if and when desirable.

After blocking, the hat takes the form generally indicated in Fig. 10 in which, as usual, the brim D extends substantially horizontally from the upstanding crown E.

Ordinarily the treatment of the hat, after blocking to the form indicated in Fig. 10, involves only the usual finishing and pouncing, which may or may not be applied to the reinforced edge B', as may be desired. The extreme edge of the reinforcement B' need not be rounded or cut or otherwise worked to size. Both the final size and the final finish of the reinforcement B' is ordinarily attained at the completion of the sizing or shrinking operation, the stage indicated in Figs. 7 and 8. It will be understood, however, that my invention is not so limited, and that, after sizing, the reinforcement B' may be further operated upon in any desired way as, for example, by ironing or pressing the brim D at the point where it merges into the reinforcement B', effecting somewhat more abrupt offset of the face of the band B' from the face of the brim as more clearly indicated in Fig. 11.

In Figs. 10 and 12, there is indicated the addition of the thickening or reinforcement F as effected for example by the channel 14, Fig. 9, of both the brim D and crown E at and adjacent their junction.

The edge reinforcement B', produced as above described, and the same is generally true of reinforcements such as F, is most effective; it is, in a mechanical sense, strong; it is homogeneous, and its integral union with the brim is homogeneous therewith and of great strength. It is simple and plain in structure, because it is single-ply or a single element, and is not composed of or built up from two or more layers or components, and

is devoid of stitching, either temporary or permanent, and requires after initial formation, no turning, folding, working, welding, 5
welting or the like. In fact it is elementally simple, and is structurally formed entirely during the deposit of the hat body as a whole upon the cone; and thereafter it requires no 10
working or treatment, because in the usual sizing or shrinking operation it takes its final form and dimensions, without need for cutting, trimming, rounding or other operation.

Because of its characteristics aforesaid, and due to its method of manufacture, it is 15
very low in cost, for in its production there is involved no folding, stitching, manual felting together or welding of parts, or any other significant operation.

The reinforcement B' or F is homogeneous 20
or jointless throughout, in the sense that it is without such a joint as is occasioned by more or less complete intermingling, welding or mutual penetration of two or more layers of felt or like material.

25
For brevity in the appended claims the term "fur" includes hairs of fur bearing animals, wool and other fibers, and felt producing materials in general.

30
Hat brims of the character hereinbefore described are claimed in Letters Patent of the United States No. 1,848,832, granted March 8, 1932, on my application Serial No. 531,933, filed April 22, 1931.

35
What I claim is:

1. Apparatus for producing hat bodies of felt, comprising a perforated cone having a circumferentially extending external perforated channel, and means for exerting suction through the perforations of the cone and channel.

2. Apparatus for producing hat bodies of felt having defined brim edges thicker than the adjacent portions of the brim, comprising a perforated cone terminating at its end in a circumferentially extending external perforated channel, and means for exerting suction through the perforations of the cone and channel.

3. Apparatus for producing hat bodies of felt, comprising a perforated cone having an imperforate base, an imperforate inwardly extending flange on said base, a perforated circumferentially extending external recess in said cone terminating at said flange, and means for exerting suction through the perforations of said cone and recess.

4. Apparatus for producing hat bodies of felt, comprising a perforated cone having intermediate its ends a circumferentially extending external perforated channel, and means for exerting suction through the perforations of the cone and the channel.

5. Apparatus for producing hat bodies of felt, comprising a perforated cone having a

circumferentially extending perforated external channel, and means for exerting suction through the perforations of the cone and channel, the perforations of said channel being larger than the perforations of the adjacent portion of the cone.

6. Apparatus for producing hat bodies of felt having defined brim edges thicker than the adjacent portions of the brim, comprising a perforated cone terminating at its end in a circumferentially extending perforated external channel, and means for exerting suction through the perforations of the cone and greater suction through the perforations of said channel, the perforations of said channel being larger than the perforations of the adjacent portion of the cone.

7. Apparatus for producing hat bodies of felt, comprising a perforated cone having an imperforate base, an imperforate inwardly extending flange on said base, a perforated circumferentially extending external recess in said cone terminating at said flange, and means for exerting suction through the perforations of said cone and greater suction through the perforations of said recess.

8. Apparatus for producing hat bodies of felt, comprising a perforated cone, means for delivering fur adjacent the cone, means for exerting suction through the perforations of the cone, and means for independently delivering fur from said first named means to a circumferential zone of said cone, whereby there are produced in said zone deposits of said fur thicker than and integral with the deposit external to said zone.

9. Apparatus for producing hat bodies of felt, comprising a revolving perforated cone having a circumferentially extending perforated channel, means for delivering fur adjacent the cone, means for exerting suction through the perforations of the cone and channel, and means for independently delivering fur substantially directly to said channel, whereby there is produced at said channel a deposit thicker than and integral with the deposit external to said channel.

10. Apparatus for producing hat bodies of felt, comprising a chamber, a perforated cone revolving therein, means for exerting suction through the perforations of said cone, structure for delivering fur to said chamber, a conduit conducting fur from said structure to a circumferential zone of said cone, whereby there is produced in said zone a deposit thicker than and integral with the deposit external to said zone, and means for withdrawing the discharge of said conduit from said cone upon completion of deposit thereon.

11. Apparatus for producing hat bodies of felt, comprising a chamber, a perforated cone revolving therein, means for exerting suction through the perforations of said cone, structure for delivering fur to said chamber,

a conduit conducting fur from said structure to a zone of said cone, and means for exerting suction, greater through said zone than through the adjacent portions of said cone, whereby there is produced in said zone a deposit thicker than and integral with the deposit external to said zone.

12. Apparatus for producing hat bodies of felt with integral defined brim edges thicker than the adjacent portions of the brims, comprising a perforated cone, an abutment at the limit of the perforations of the cone, and means for exerting suction through the perforations of the cone with greater suction in a zone immediately adjacent said abutment whereby the thickened deposit in said zone has at said abutment a substantially regularly defined end.

13. Apparatus for producing hat bodies of felt with integral defined brim edges thicker than the adjacent portions of the brims, comprising a perforated cone terminating in a perforated channel, an abutment at the limit of the perforations of said channel, and means for exerting suction through the perforations of the cone with greater suction at said channel, whereby the thickened deposit in said channel has at said abutment a substantially regularly defined end.

14. In the manufacture of hats, the method of producing a hat body, which comprises depositing fur to produce a body, and producing a defined reinforced edge on the brim-forming portion by simultaneously depositing fur integrally and homogeneously with the body in a defined zone at its edge to a thickness greater than the immediately adjacent brim-forming portion of said body.

15. In the manufacture of hats, the method of producing a hat body, which comprises depositing fur to produce a body, and producing a defined reinforced edge on the brim-forming portion with an end of defined regularity by simultaneously depositing fur integrally and homogeneously with the body in a defined zone at its edge to a thickness greater than the immediately adjacent brim-forming portion of said body, and substantially sharply defining the free end of said edge.

16. In the manufacture of felt hats, the method which comprises depositing fur to produce a body, causing the fur to be deposited, at the free end of the brim-forming portion of said body, against a defining and limiting surface, and thereafter working the body into a structure whose brim portion comprises a regularly defined untrimmed free end.

17. In the manufacture of hats, the method of producing a felt brim having a defined reinforced edge thicker than and homogeneous and integral with the immediately adjacent portion of the brim, which comprises depositing fur to produce a body, effecting si-

multaneous deposit of fur integrally and homogeneously with the body in a defined zone at its edge to a thickness greater than the immediate adjacent brim-forming portion of said body, and thereafter sizing said body and edge.

18. In the manufacture of hats, the method of producing a felt brim having a defined reinforced edge thicker than and homogeneous and integral with the immediately adjacent portion of the brim, which comprises depositing fur to produce a body, and producing a defined reinforced edge with an end of defined regularity by simultaneously depositing fur integrally and homogeneously with the body in a defined zone at its edge to a thickness greater than the immediately adjacent brim-forming portion of said body, substantially sharply defining the free end of said edge, and thereafter sizing said body and edge to form a body having a defined reinforced untrimmed edge thicker than and homogeneous and integral with the sized immediately adjacent portion of the brim.

19. In the art of manufacture of felt hats, the method which comprises depositing fur from a source thereof to produce a body, simultaneously depositing a portion of the fur, independently conducted from said source, on the body during its formation in a substantially definite zone of said body to produce a defined reinforced band thicker than and homogeneous and integral with the immediately adjacent portion of the body.

20. In the art of manufacture of felt hats, the method which comprises depositing fur from a source thereof to produce a body, simultaneously depositing a portion of the fur, independently conducted from said source, on the body during its formation in a substantially definite zone at its end to produce a defined reinforced edge thicker than and homogeneous and integral with the immediately adjacent brim-portion of the body.

21. In the manufacture of felt hats, the method which comprises depositing fur upon a surface to produce a body to be worked into crown and brim portions of a hat, and simultaneously depositing a portion of the fur in a defined depression in said surface at its end to a thickness greater than that of the immediately adjacent portion of the brim-forming portion of said body to form a defined band integral and homogeneous therewith and adapted to be worked into a defined reinforced brim edge thicker than the immediately adjacent portion of the brim and homogeneous and integral therewith.

22. In the manufacture of felt hats, the method which comprises depositing fur upon a surface to produce a body to be worked into crown and brim portions of a hat, and simultaneously depositing a portion of the

fur in a defined depression in said surface at its end and against an end-defining surface to a thickness greater than that of the immediately adjacent portion of the brim-forming portion of said body to form a defined band, having a substantially sharply defined end, integral and homogeneous with said brim-portion and adapted to be worked into a defined reinforced untrimmed brim edge thicker than the immediately adjacent portion of the brim and homogeneous and integral therewith.

CERTIFICATE OF CORRECTION.

Patent No. 1,915,063.

June 20, 1933.

GEORGE V. MacKINNON.

It is hereby certified that error appears in the printed specifications of the above numbered patent requiring correction as follows: Page 4, lines 80, 81, and 82, claim 6, strike out the comma and words ", the perforations of said channel being larger than the perforations of the adjacent portion of the cone"; page 5, line 15, claim 12, after "abutment" insert a comma; and line 69, claim 17, for "immediate" read immediately; and that the said Letters Patent should be read with these corrections therein that the same may conform to the record of the case in the Patent Office.

Signed and sealed this 21st day of November, A. D. 1933.

F. M. Hopkins
